US00D896214S

(12) **United States Design Patent** (10) **Patent No.:** **US D896,214 S**
(45) **Date of Patent:** **** Sep. 15, 2020**

(54) **CASE FOR ELECTRONIC COMMUNICATIONS DEVICE**

(71) Applicant: **SPIGEN KOREA CO., LTD.**, Seoul (KR)

(72) Inventor: **Jong Hwa Lee**, Seoul (KR)

(73) Assignee: **Spigen Korea CO., LTD.**, Seoul (KR)

(**) Term: **15 Years**

(21) Appl. No.: **29/724,113**

(22) Filed: **Feb. 12, 2020**

Related U.S. Application Data

(63) Continuation of application No. 29/681,411, filed on Feb. 25, 2019, now Pat. No. Des. 879,084.

CLAIM

The ornamental design for a case for electronic communications device, as shown and described.

DESCRIPTION

FIG. 1 is a front perspective view of a case for electronic communications device in an open position showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view thereof in a closed position, shown in an environment of use;

FIG. 10 is a rear perspective view thereof in a closed position, shown in an environment of use;

FIG. 11 is a front perspective view thereof in an open position, shown in an environment of use; and,

FIG. 12 is a rear perspective view thereof in an open position, shown in an environment of use.

The broken lines depict environmental subject matter and portions of the case for electronic communication device that form no part of the claimed design.

1 Claim, 12 Drawing Sheets
